UNITED STATES PATENT OFFICE.

CHARLES S. HEATH, OF PETOSKEY, MICHIGAN.

BLOCK-TRIMMING MACHINE.

Application filed August 17, 1921. Serial No. 493,043.

To all whom it may concern:

Be it known that I, CHARLES S. HEATH, a citizen of the United States, residing at Petoskey, in the county of Emmet and State 5 of Michigan, have invented certain new and useful Improvements in Block-Trimming Machines, of which the following is a specification.

This invention relates to a block trimming machine, and one particularly adapted for trimming surfaces of meat-chopping and similar blocks so as to maintain a smooth surface on the block.

The prime feature of the invention is the 10 provision of means for driving the cutting disk and so constructing and arranging said driving means that it may be used with either a direct or alternating current.

A further feature of the invention is the 15 means of connecting the cutting device with the driving means whereby a maximum driving power will be derived, while the cutting element is driven at a minimum speed.

20 A further feature of the invention is in so constructing the parts of the trimmer that an air chamber or space is provided between the lower face of the trimming element and the face of the trimmed portion 25 of the block thereby eliminating friction between the cutting element and the face of the block.

Other objects and advantages will be hereinafter more fully set forth and pointed 30 out in the accompanying specification.

In the accompanying drawings,

Figure 1 is a top plan view of the device, parts being shown in section,

Figure 2 is a sectional view as seen on 40 line 2—2, Figure 1,

Figure 3 is a sectional view as seen on line 3—3, Figure 1,

Figure 4 is a sectional view as seen on line 4—4, Figure 3,

45 Figure 5 is a perspective view of a hood for the cutting element, and

Figure 6 is a diagrammatic view of a switch mechanism for controlling the driving elements.

50 Referring to the drawings, 1 indicates a housing in one end of which is formed a bearing 2, and extending through said bearing is a shaft 3, the lower end of said shaft having any suitable form of cutting ele-

55 ment 4 attached thereto, said element being employed for trimming or cutting off the

top surface of a meat chopping block for removing any inequalities in the surface of the block.

In order to obviate the necessity of providing a different motor for different currents encountered, such as a direct current or alternating current, and at the same time increase the driving power for the shaft 3 and the cutting element attached thereto, 60 two or more motors 5 and 6 are mounted in the housing 1, which are wound universal, and as shown in the diagrammatic view of Figure 6, are wired in parallel or series, thereby adapting the motors for any suitable 65 electric current.

In Figure 6 the poles A are connected with a double pole double throw switch, and when a light current is being used, say 110 volts, the switch is moved to the contacts 75 B, thus connecting the motors in parallel, and when a higher voltage is used, say 220, the switch is moved to engagement with the contacts C, thereby connecting the motors in series. The multiple motors are 80 arranged for driving the shaft 3 by connecting gears 7 to the rotors of the motors 5 and 6, and interposing a gear 8 between the gears 7, said gear 8 being mounted upon a shaft 9 to which is connected a bevel gear 85 10, said shaft 9 passing through a bearing 11 on the housing 1, the gears 7 being of a less diameter than the diameter of the gear 8. The bevel gear 10 in turn meshes with a bevel gear 12 on the shaft 3 and by means 90 of which said shaft and the cutting element attached thereto are driven, and by connecting the motors to the shaft 3 through the medium of the various gears, as shown, the driving power of the motors will be 95 greatly enhanced while the revolution of the cutting element will be lowered.

In order to provide an air space between the cutting element and the surface being trimmed, thereby eliminating friction between the face of the cutting element and the face of the block, the shaft 3 is set at such an angle that the advancing and cutting portions 4^a and 4^b, of the cutting edge of the element 4, will be in a plane lower than 100 the remainder of the cutting element, thereby disposing the lower face of the cutting element at such an angle as to leave an air space therebetween and the trimmed face 105 of the block.

Heretofore, the cutting element has been mounted so as to rest flat upon the trimmed 110

surface which caused extensive friction, and to such an extent as to materially interfere with the action of the cutting element, as well as charring the surface of the block. 5
5 By tilting the cutting element as shown in Figures 3 and 4, and thus providing an air space below the cutting element, these objectionable features are entirely overcome, while the tilt is so slight that the surface 10 of the block will, to all appearances, be perfectly flat.

The housing 1 is preferably provided with channelled rollers 13, which are adapted to travel over a trackway 14, said trackway 15 being in turn mounted upon a carriage 15, the carriage 15 being in turn mounted upon a trackway 16. By mounting the housing in this manner the cutting element may be moved back and forth over the surface of 20 the object being trimmed or cut off, consequently the entire surface of the chopping block may be treated without resetting the carriage and trackway upon which it is mounted other than the travel of the carriage and the housing mounted thereon over the surface of the block.

The cutting element 4 is preferably covered over with a hood 17, which has a collar 18 for engagement with bearing 2, 30 binding screws 19 being employed for securing the hood to the bearing, and the hood may have a removable section 20, for convenience of removing or attaching the hood without removing the cutting element 4. 35 The edge of the hood 17 adjacent the point of contact of the cutting element with the surface being removed is provided with an opening 21, the end walls of which bear against the surfaces of the portions being 40 trimmed, while at a point substantially diametrically opposite the opening 21 is a discharge nozzle 22.

By providing two or more motors with universal winding and wiring them together 45 in parallel or series, a universal driving element is provided and may receive current from either direct or alternating currents; consequently but one form of motor is required, while with the present mode of driving cutters of this class a motor must be used adapted for one particular kind of current while a different motor is required with a different current, consequently necessitating the carrying of a variety of motors peculiar-

ly adapted to the class of current provided. 55 In addition to adapting the driving elements for use in connection with all kinds of currents, by tilting the cutting element as shown in the drawings and providing the air space below the cutting element, far lighter motors 60 will give the same or greater driving power to the cutting element than would be possible with the cutting element resting flat against the surface being trimmed. In other words, two universal motors weighing sub- 65 stantially 21½ pounds each, running at a speed of 10,000 R. P. M., of 5/8 H. P. each and geared to the cutting element as shown and described, will develop a greater pulling torque than a motor rated at 2½ H. P., and 70 weighing approximately 260 pounds. Furthermore, by tilting the cutting element, the temper will not be drawn from the cutting element by over-heating, and neither will the surface of the block be charred. 75

It will further be seen that by mounting the motors horizontally and connecting them to the shaft 3 as shown, the weight of the motors is entirely removed from said shaft, which is very essential in eliminating vibration or chattering prevalent in machines having the motor mounted directly upon the shaft carrying the cutting element. 80

It will be understood, of course, that while the motors are shown as driving a block 85 trimming element they may be applied for driving other elements, such as meat grinders, slicers, and the like.

Having thus fully described my said invention, what I claim as new and desire to 90 secure by Letters Patent, is:

In a block surfacing machine a portable track, a truck carriage movable along said track, a track on the truck at an angle to the first named track, a carriage movable on the second track, a surfacing tool at the front end of the carriage having its working edge below the level of the first named track, an inclined shaft supporting the tool in inclined relation to the work, a pair of horizontal 95 shafts geared to the inclined shaft and independent motors driving respective horizontal shafts, substantially as set forth.

In witness whereof, I have hereunto set my hand and seal at Petoskey, Michigan, 100 this 6th day of August, A. D. nineteen hundred and twenty-one.

CHARLES S. HEATH. [L. S.]
